(57) **CLAIM**

The ornamental design for a personal watercraft, as shown and described.

DESCRIPTION

FIG. 1 is a right side elevation view of a personal watercraft according to our design;

FIG. 2 is a front elevation view of the personal watercraft of FIG. 1;

FIG. 3 is a left side elevation view of the personal watercraft of FIG. 1;

FIG. 4 is a rear elevation view of the personal watercraft of FIG. 1;

FIG. 5 is a top plan view of the personal watercraft of FIG. 1;

FIG. 6 is a bottom plan view of the personal watercraft of FIG. 1;

FIG. 7 is a perspective view taken from a front, right side of the personal watercraft of FIG. 1;

FIG. 8 is a perspective view taken from a rear, right side of the personal watercraft of FIG. 1;

FIG. 9 is a perspective view taken from a front, left side of the personal watercraft of FIG. 1; and,

FIG. 10 is a perspective view taken from a rear, left side of the personal watercraft of FIG. 1.

Throughout the Figures, where shown, the broken lines showing additional structure of the personal watercraft are for illustrative purposes only and form no part of the claimed design.

1 Claim, 10 Drawing Sheets
